UNITED STATES PATENT OFFICE

CHARLES TUTEUR, OF CHICAGO, ILLINOIS

DESIGN FOR A STAND FOR SMOKER'S AND SIMILAR ARTICLES

Application filed August 3, 1931. Serial No. 40,763. Term of patent 3½ years.

To all whom it may concern:

Be it known that I, CHARLES TUTEUR, a citizen of the United States, and resident of Chicago, in the county of Cook and State of Illinois, have invented a new, original, and ornamental Design for a Stand for Smoker's and Similar Articles, of which the following is a specification, reference being had to the accompanying drawings, forming a part thereof.

Figure 1 is a view in perspective of a stand for smokers' and similar articles, showing my new design.

I claim:

The ornamental design for a stand for smoker's and similar articles, as shown.

Signed at Chicago, in the county of Cook and State of Illinois, this 18th day of July, A. D. 1931.

CHARLES TUTEUR.
